UNITED STATES PATENT OFFICE

RALPH H. TOWNSEND, OF MOUNT VERNON, NEW YORK, ASSIGNOR TO THE BRUNSWICK-BALKE-COLLENDER COMPANY, OF WILMINGTON, DELAWARE, A CORPORATION OF DELAWARE

SOUND RECORDING AND REPRODUCING APPARATUS

Application filed January 13, 1925. Serial No. 2,064.

This invention relates to apparatus for recording and reproducing sounds electrically and is directed to the provision of electric recording and reproducing apparatus of an improved construction whereby more faithful reproduction of recorded sounds may be obtained.

The invention may be employed in a recorder actuated by the fluctuations of electric current flowing in a circuit to oscillate a suitable stylus and thereby cut or otherwise form a record groove whose undulations correspond with the sound variations. Or, the invention may be embodied in a reproducer in which an oscillating member is oscillated by the undulations of a record groove and generates a fluctuating current in an electric circuit. This circuit may be extended to a sound reproducer located at a desired point and if the fluctuating current is of insufficient strength to develop the required volume of sound it may be amplified by including in the circuit a suitable audio-frequency cascade amplifier using resistance coupling between successive stages.

The improved sound recording and reproducing apparatus includes a magnet, which may be either a permanent magnet or an electro-magnet, and may have either a solid or a laminated core, and a pivotally mounted member cooperating therewith as an armature. Associated with these parts is a coil included in a circuit in which a fluctuating current flows, this current being employed to effect the oscillation of the armature in the case of a recorder or being developed in the circuit by the oscillation of the armature when the latter is actuated by a sound record. Sound recording and reproducing apparatus of this general character has been made heretofore and it is the object of this invention to provide an improved construction for such apparatus whereby superior results are obtained, all to the end that more faithful reproductions of recorded sounds may be obtained.

The improved construction concerns more particularly the construction and arrangement of the pivoted armature. This is made of very light weight, as light as is possible

without sacrificing rigidity to too great an extent. It should be rigid to a high degree so that oscillations imparted to it will not be absorbed in it to any appreciable extent and by making it of very light weight it will respond more promptly and more accurately to the forces applied to it tending to oscillate it. It is pivoted at a point close to its center of inertia for in that way also greater accuracy of response in movement of the armature to the forces applied to it is obtained.

Parts on this armature are disposed between or adjacent to the poles of the magnet but the width of the air gap between these parts and the poles is made large relatively to the range of oscillation of the parts of the armature so that these parts are at all times spaced from the poles of the magnet by a considerable distance. When the armature is in its normal or mid-position, it is acted upon equally by the two poles, but when it is moved to carry one part closer to a pole, that pole immediately becomes more effective to attract the armature still closer to it. By making the width of the air gap large compared to the range of movement of the parts of the armature, the effect of this increasing attractive power of the pole as the part of the armature moves toward it is minimized and this may be to such extent that it is practicably negligible.

In reproducing and recording apparatus of this type, it is necessary to provide a suitable means for damping the movements of the armature by holding it yieldingly in its mid position and tending to return it to that position when it has been moved from it. One of the features of the present invention involves the provision of an improved form of damping means. The use of a spring or elastic diaphragm has heretofore been proposed for this purpose but with a damping means of this form the results obtained are much less perfect than is desired. If the spring or diaphragm is made relatively stiff it imposes too much resistance to the desired oscillatory movements of the armature, and on the other hand if it is made less stiff so that its resistance is not too great, its own resonance characteristics are impressed upon

the armature and affect detrimentally the results obtained.

I have procured far superior results by the use of a damping means in the form of a sponge rubber packing bearing upon the armature and compressed more or less by the oscillatory movements thereof. Such a non-metallic, non-resonant packing holds the armature yieldingly in its mid position. 5 and serves adequately to return it to that position when it has been moved and there is an entire absence of the super-position upon the armature of a foreign resonance characteristic. Also, with such a damping means provision for regulation can be made quite readily as for instance by the use of a screw or similar means for compressing the rubber packing more or less as may be required. 10 15 20 25 30 35 40 45 50 55 60

The invention may be embodied in a form employing a magnet having its poles facing each other, and an armature in the form of a straight bar of considerable rigidity pivoted at about its center and with one end lying between the two pole faces. This end of the bar may also extend through a coil connected in an electric circuit so that the coil receives the fluctuating electric current which effects the oscillation of the armature or has such a current developed in it by the oscillation of the armature. The width of the gap between the pole faces is made large with relation to the range of oscillation of the armature and the soft rubber which constitutes the damping means is mounted in the gap of the magnet and bearing upon opposite sides of the armature. Or if desired, the poles of the magnet may face in the same direction and the light, rigid, pivoted armature may be bifurcated on one side of its pivot to provide arms extending in proximity to the poles; also, if desired the coil may encircle some portion of the magnet instead of the armature. Whatever the construction may be in these respects, the construction characteristic of the invention involves the use of a light rigid armature pivoted at a point adjacent to its center of inertia and having parts adjacent to the poles 65 of the magnet, the range of oscillation of the armature being small compared to the gap between the pole faces and the adjacent faces of the armature, together with damping means for holding the armature yieldingly in its central position, this damping means being preferably in the form of the soft rubber packing above referred to.

I have illustrated in the drawings annexed hereto embodiments of the invention with which good results may be obtained. 60 In these drawings, Fig. 1 is a face view of a sound recorder embodying the invention, partly in section on line 1—1 of Fig. 2; Fig. 2 is a side view of the construction shown 65 in Fig. 1; Fig. 3 is a view of the recorder

showing the face opposite that shown in Fig. 1; Fig. 4 is a partial horizontal section on the line 4—4 of Fig. 1.

Referring first to Figs. 1 to 4, a permanent magnet is shown at 7 of the usual horse-shoe form having its poles turned toward each other and an air gap of substantial size between the poles faces. This magnet is secured by a strap 8 and screw 9 to a frame piece 10 on which is formed a socket 11 to receive the end of the supporting arm by which the recorder is moved across the face of a disc sound record while cutting a record groove therein. At its lower edge the frame piece 10 is turned laterally at 12 to form a bracket to which is secured a support 13. The armature is pivotally mounted upon this support. In the present instance of a sound recorder, this armature 14 is a cutter bar adapted to have a suitable cutting jewel secured to its lower end. In the case of a reproducer the armature would be a stylus bar having secured to its lower end a stylus adapted to track in the groove of a sound record. In either case the armature would be a light rigid bar, made as light as possible without sacrificing rigidity to too great an extent, and pivotally mounted at about its center of inertia. In the present instance the armature is shown as integral with a horizontal member 15, both ends of which are pointed and fit in bearings. One of these bearings is formed in a stud 16 on the support 13 and the other is made adjustable by being formed in the end of a stud 17 threaded in a bracket 18 on the support 13. With this form of mounting vibrational movement of the armature relative to its bearings which would give rise to what is known as chattering is prevented. 105 110 115 120 125 130

The upper end of the armature extends up into the space between the pole faces of the magnet 7 and surrounding this portion of the armature is a coil 23 which is mounted upon the bracket 12. The ends of this coil are electrically connected to terminals 24 mounted on a block 25 of insulating material secured to the frame 10. The damping means for the armature 14 consists of two rectangular blocks 26 of sponge rubber, each fitting between one of the pole faces of the magnet 7 and the adjacent side of the upper end of the armature 14 and both of them resting upon the top surface of the spool on which the coil 23 is wound. 115 120 125 130

The construction of the invention thus described is distinctive in the respects that the armature is a rigid light member pivotally mounted at about its center of inertia and having parts which lie adjacent to the pole faces of the magnet, the oscillations of this armature being suitably damped and occurring within such a range that the parts of the armature adjacent to the pole faces are always held at a sub- 120 125 130

stantial distance from those faces by reason of the width of the gap between the pole faces and the adjacent faces of the armature relative to the amplitude of oscillation of the armature. By reason of the use of this arrangement, the damping effect may be very light with the result that there will be proportional response of the movement of the armature to forces applied to it throughout the whole of its range of movement, and, in the case of a reproducer, less wear upon the record. It is well to use high silicon steel in making the armature to the end that rigidity and light weight may be combined to a high degree. For the same reason the armature may be of tubular construction or may be made of I-beam construction. The damping means is of the preferred form above referred to, namely, blocks of soft rubber which are compressed by the oscillatory movement of the armature and which serve to return the armature to its central position on the subsidence of the force which moved it from that position. The damping effect of these blocks may be regulated as desired by subjecting them to more or less pressure in any suitable manner.

When a fluctuating current is impressed upon the coil 23 of the recorder, the magnetic field developed by the coil reacts upon the field of force of the magnet 7 within which the end of the armature 14 lies and the armature is oscillated on its pivot in exact accordance with these fluctuations, following them the more accurately because of its light weight and rigidity, the arrangement of the pivot, the relation of the amplitude of its movement to the width of the air-gap of the magnet, and the damping effect of the non-metallic non-resonant blocks. In the case of a reproducer, the armature is oscillated by the tracking of the stylus carried by it in the record groove and the movements of its upper end develops a fluctuating current in the circuit of coil 23, the strength of this current being dependent upon the number of turns in coil 23, the strength of the field of magnet 7 and the rate of change of position of the armature with respect to the coil and the pole tips. The fluctuating current so produced may be led to ear-phones or similar apparatus and if it is not of sufficient strength it may be carried through an audio frequency amplifier.

I claim:

In combination, a permanent magnet having the poles thereof turned toward each other, said poles having an air gap therebetween, a frame piece, means for connecting said magnet to said frame piece, said frame piece including a portion disposed below the poles of said magnet, a support on said portion, bearings on said support, a pivot bar carried by said bearings, an armature on said pivot bar including a portion disposed in said air gap, a coil carried by said portion of the frame piece and disposed about said armature, and means in said air gap for dampening movement of said armature.

In testimony whereof I affix my signature.

RALPH H. TOWNSEND.
